CHAIR

Allan Gould, New York, N. Y.

Application November 24, 1952, Serial No. 22,425

Term of patent 14 years

(Cl. D15—8)

To all whom it may concern:

Be it known that I, Allan Gould, a citizen of the United States, residing in the city of New York, county of New York, State of New York, have invented a new, original, and ornamental Design for a Chair, of which the following is a specification, reference being had to the accompanying drawing, forming a part thereof.

Fig. 1 is a perspective view of a chair embodying my new design;

Fig. 2 is a partial top view of the seat of the chair shown in Fig. 1; and

Fig. 3 is a sectional view along line 3—3 of Fig. 1.

I claim:

The ornamental design for a chair, as shown.
ALLAN GOULD.
